UNITED STATES PATENT OFFICE.

FRED E. EARLES, OF CHICAGO, ILLINOIS, AND FRANK G. LOWE, OF DETROIT, MICHIGAN.

FLY-KILLING DEVICE.

1,261,222.

Specification of Letters Patent.

Patented Apr. 2, 1918.

Application filed May 29, 1915. Serial No. 31,280.

To all whom it may concern:

Be it known that we, FRED E. EARLES and FRANK G. LOWE, citizens of the United States, and residents of the city of Chicago, county of Cook, and State of Illinois, and of the city of Detroit, county of Wayne, and State of Michigan, respectively, have invented certain new and useful Improvements in Fly-Killing Devices, of which the following 10 is a specification.

Our invention relates to improvements in fly killing devices of the type commonly known as "fly swatters".

Fly killing devices of the character mentioned have been found objectionable for the reason that non-abrasive material has not been used and with the result that in striking a polished or other delicate surface the latter was scratched or otherwise marred. 20 Hence with a device of this character in use at the present time, the employment of the same has been restricted, the same being adapted for use only upon a surface which is not readily scratched or marred.

It is the object of this invention therefore to provide a device of the character mentioned which may be used upon any surface without fear of injuring the same. A further object is the production of a fly killing 30 device which will be of simple construction and efficient in use.

Other objects will appear hereinafter.

The invention consists in the combinations and arrangements of parts hereinafter described and claimed.

The invention will be best understood by reference to the accompanying drawing forming a part of this specification, and in which—

40 Figure 1 is a front elevation of a fly killing device embodying the invention, and Fig. 2, is a section taken on line $\alpha-\alpha$ of Fig. 1.

The preferred form of construction as 45 illustrated in the drawing comprises an elongated wooden handle 1 at one end of which is provided a flap 2. The flap 2 is formed of a thin sheet of leather or other suitable soft non-abrasive material, the same being perforated in order to permit of the passage of air therethrough in using the device. Said 50 perforations are however of small enough

size to prevent the passage of a fly therethrough.

The flap 2 is secured to the handle 1 by engagement of one edge thereof in a slot 3 provided in the end of the handle, said edge of the flap being glued to the handle and being further secured by means of a nail 4.

With this arrangement it will be seen that 60 the striking of a polished surface such as that of a table top or other article of furniture with the flap 2 will not in any way injure the same as would be the case where the flap is formed of wire mesh or other 65 abrasive material.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the 75 scope of the appended claims.

Having described our invention what we claim as new and desire to secure by Letters Patent is:

1. A fly killing device comprising a handle; and a foraminated flap on said handle of soft, non-abrasive material, having sufficient inherent stiffness and durability to serve without reinforcement, substantially as described.

2. A fly killing device comprising a handle; and a foraminated flap on said handle of soft leather, substantially as described.

3. A fly killing device comprising a handle; and a flap on said handle formed of a perforated sheet of soft flexible non-abrasive material, substantially as described.

4. A fly killing device comprising a handle; and a thin perforated piece of leather secured to one end of said handle, substantially as described.

In testimony whereof we have signed our names to this specification in the presence of two subscribing witnesses.

FRED E. EARLES.

FRANK G. LOWE.
